(57) **CLAIM**

The ornamental design for a cordless power tool, as shown and described.

DESCRIPTION

FIG. 1 is a perspective view of the cordless power tool, a battery unit and a lanyard attached to the cordless power tool being shown in broken line;

FIG. 2 is a perspective view as shown in FIG. 1 with the battery unit and lanyard being removed;

FIG. 3 is a left side view thereof; the right side view is not shown as it is a mirror image of the left side view;

FIG. 4 is a rear elevational view thereof;

FIG. 5 is a front elevational view thereof;

FIG. 6 is a top plan view thereof; and,

FIG. 7 is a bottom plan view thereof.

The broken lines are shown in the views for illustrative purposes only and form no part of the claimed invention.
